Mossberg Pressed Steel Corporation, a corpora-
tion of Massachusetts

Application May 31, 1933, Serial No. 673,704

15 Claims. (Cl. 242—110)

This invention relates to a swift and has for one of its objects the provision of a swift which will be adjustable throughout a wide range that it may receive skeins of yarn of widely varying sizes.

Another object of the invention is the provision of a swift which may be easily collapsed to a sufficient extent to permit the yarn to be easily positioned thereon after which it may expand to securely engage the yarn.

Another object of the invention is the provision of a swift which, when empty, may be taken from the frame on which it is positioned with one hand and at the same time collapsed while the other hand is utilized for positioning a skein of yarn about the same.

A further object of the invention is the provision of a swift which will be light in weight to reduce the inertia of the device and also will not excessively fatigue the operator who must lift it from the frame for the positioning of skeins of yarn thereon to be drawn to the spools or bobbins upon which they are to be wound.

With these and other objects in view, the invention consists of certain novel features of construction, as will be more fully described, and particularly pointed out in the appended claims.

In the accompanying drawings:

Fig. 1 is the side elevation of the swift in collapsed position.

Fig. 2 is an edge view thereof.

Fig. 3 is a side elevation of the swift in full expanded position.

Fig. 4 is a fragmental detail illustrating on a somewhat larger scale the joint between two of the arms when the device is in contracted position and the arms spread apart.

Fig. 5 is a view similar to Fig. 4 showing the arms close together when the device is in expanded position.

Fig. 6 is a fragmental detail in perspective of the end portion of one of the arms illustrated in Figs. 4 and 5.

Fig. 7 is a view similar to Fig. 6 showing the other arm of the portion shown in Figs. 4 and 5.

Fig. 8 is a perspective view of the member for connecting the yarn holder to the arms.

Fig. 9 is a perspective view of a washer positioned between the arms.

Fig. 10 is a sectional view on line 10—10 of Fig. 4.

Fig. 11 is a sectional view on line 11—11 of Fig. 1, showing the stop for limiting the expansion of the swift.

Fig. 12 is a sectional view substantially on line 12—12 of Fig. 3.

Fig. 13 is a sectional view through the two hub members of the swift.

Fig. 14 is a fragmental view of one of the members and taken on substantially the line 14—14 of Fig. 13 looking in the direction of the arrow.

Fig. 15 is a section on line 15—15 of Fig. 13.

Fig. 16 is a sectional view of a modified form of stop which may be positioned on one of the arms to limit the expansion of the swift.

In the manufacture of yarn it is frequent that skeins, when taken from the skeining machine, will be positioned upon a swift to be drawn therefrom to spools or bobbins, and as one of these skeins runs out it is necessary that the swift be removed from the frame and a fresh skein placed thereon. In placing of the skeins in position some sort of contraction is desirable that the skeins may be easily positioned on the strings between the usual sticks on the swift. It is frequent also that where skeins of different size are used it is necessary to provide separate swifts for each size skein, and in order that a swift may be provided which may be easily adjustable to accommodate widely varying size skeins and also be collapsible to a considerable extent to allow a skein to be easily positioned thereon I have provided a device which is collapsible by reason of its parts folding one on the other which may be made light in weight and which may be limited in its adjustment by suitable stops and one which the operator may manipulate by a single hand while using the other hand to put the same thereon, and the following is the description of the present embodiment of this invention illustrating the preferred means by which these advantageous results may be accomplished.

With reference to the drawings I provide a bearing means at the center of the swift designated generally 20 which may be pivotally mounted in bearings in the usual manner. This bearing means in the present construction consists of a spindle 21 having its ends reduced as 22 to provide trunnions. A hub 23 is secured against longitudinal movement on the spindle by a bushing 24 fitted within a hole 25 in the hub and held in place by set screw 26. Another hub 27 is held against longitudinal movement of the spindle by collar 28 held in position by set screw 29. This collar being set within a recess 30 in the end of the hub 27. The hub 27 is rotatable about the spindle as an axis. A spring 31 mounted within recesses, 32 in hub 23, and 33

in hub 27, is held in position by reason of the end portions 34 and 35 of this spring extending into openings 36 and 37 in the hubs. A washer 21^a is interposed between the ends of the spring 5 and the adjacent wall of the recess. These hubs are relatively rotated to cause the spring to be under tension when the device is in collapsed position whereby they tend to relatively rotate to expand the device.

- 10 The inner surfaces of the hubs are each slotted as at 38 and 39 which provides grooves to receive the flattened portions 40 and 41 of the members 42 and 43 which members are secured to their respective hubs and in the grooves by screws 44. 15 The shaft 21 extends through the openings 45 in the members 42 and 43. These members 42 and 43 are shaped with offsets or bends as at 46 and 47 in order that they may be better grasped by the hand of the operator for manipulating them.

10 A pair of links or arms 48, 49 are pivoted together as at 50 and are also pivoted to the ends of the members 42 and 43 as at 51 and 52. These pairs of links or arms are duplicated at either 25 side of the device as it appears in Figs. 1 and 3. At the points 51 and 52 guides 53 are also mounted, and also at each of these pivot points arms 54 and 55 are pivoted, the arm 54 being pivoted to the arm 42 and extending upwardly as shown 30 in Fig. 3 through the guide 53 while the arm 55 is pivoted as at 51 to the arm 43 and extends downwardly through the guide 53 mounted on pivot 52. These arms 54 and 55 are likewise 35 duplicated on the other side of the center of the device whereby a symmetrical arrangement is afforded.

At the ends of the arms 54 and 55 yarn holders 56 are rigidly secured, each consisting of a bridge portion 57 with flanges 58 extending outwardly. These flanges are notched as at 59 that a cord may be stretched across them if it is desired that the yarn rest upon a cord rather than on the rigid yarn holder 56.

Yarn holders 56 are pivotally related at the 45 junction points 50 of the links or arms 48 and 49. In this instance the flattened end portion 60 of the arm 48 and the flattened end portion 61 of the arm 49 are each notched as at 62 and 63. A washer 64 is positioned between these flattened 50 portions while a mounting member 65 having a bridge portion 66 and eyes 67 mounted on either side of the flattened portions 60 and 61 all receive the pivot pin 68, the notch 69 of the washer 65 fitting the portion 66 of mounting member 65, and this portion 66 fitting within the notches 62 and 63 of the arms 48 and 49 whereby the 55 yarn holder 56, which is rigidly secured to the portion 66, is limited in its swinging movement about the pivot 68 by reason of its engagement with the edges of notches 62 and 63. In some 60 positions of adjustment, such as when the device is in expanded position and the arms are in the position illustrated in Fig. 5, the yarn holder 56 can then practically not rock at all whereas when the device is in contracted position and the arms are in the position illustrated in Fig. 4, a limited 65 rocking movement of the parts is had. In this manner the yarn holders are retained in their desired position.

70 It will thus be observed that as I swing the arms one with reference to the other about the pin 21 as a bearing from the position illustrated in Fig. 3 to the position illustrated in Fig. 1 all of the yarn holders will be moved inwardly 75 so that their radial distance from the bearing

is shorter. This movement places the spring 31 under tension, and if released this spring will cause the hubs to rotate and the arms to move outwardly from the contracted position in Fig. 1 to the expanded position in Fig. 3 whereby each of the yarn holders is then radially moved a distance outward from the bearing so that a skein of larger encircling size may be mounted thereon. The position of the skein on the swift being illustrated by the dotted line A in Fig. 1.

10 The spring 31 will be placed under some tension when the device is assembled so that full reliance for expansion does not depend upon the pressure under which the spring is placed by the contraction. In order that the expanding movement, urged by the spring, may be limited I have provided a clamp 70 which may be secured about the rounded portion of one of the arms 55 and clamped at a desired position therealong by means of a stud 72 having a finger piece 73 to bind the two portions 74 and 75 thereof together, and by reason of the engagement of this stop with the guide through which each of these arms pass it will limit the expanding movement of the swift.

20 In some instances in order that it will not be necessary to unscrew the clamp for movement in one direction I may provide a ball clutch grip in which there is a cup 76 slidably mounted upon the rod or arm 55, and which has therein a member 77 in the recess 78 therein to receive balls 79 and engage the tapered surface 80 of the cup 76. The spring 31 tends to force the balls into engagement with the tapered surface of the arm 55 while permitting movement of the device in the direction of the arrow 82, and preventing its movement in the opposite direction by reason of the wedging action obtained between the tapered surface and the arm on which the device is mounted. Should, however, it be desired to move the device in a direction opposite to the arrow 82, the head of the member 77 would be engaged and moved relatively to the cup 76 to release the balls from gripping the rod 55 and permit relative movement therealong.

30 In this particular swift the hubs are provided with flattened portions 83 which enable a friction brake to be applied for retarding its rotation by placing tension upon the swift, and also they are grooved as at 84 in order that the hanging type 35 weight or tension may be placed to retard the 40 rotation of the swift.

45 The device will preferably be made out of light weight metal such as aluminum or a light alloy and will be of weight substantially of that of a 50 wooden swift which an operator may easily handle. Another advantage of the swift being light in weight is that the inertia of the same will be a minimum whereby the swift may be 55 easily started up by pulling on the thread and when the pull on the thread tending to rotate the same is stopped the swift will have less tendency to overrun. Also by reason of its arrangement an adjustability of about fifty per cent of its minimum size may be had so that widely varying diameters of skeins may be received, and by reason of its being collapsible by one hand, the 60 operator may use one hand to grip the same for collapsing while the other hand may be used for 65 positioning the yarn between the flanges 58 of 70 the yarn holders mounted at the ends of the arms.

75 It will also be noted that my construction is made from duplicate parts, each of the hubs being of the same construction, the members 46

and 47 being of duplicate construction, the arms being of duplicate construction, etc. throughout the entire device whereby the manufacturing costs may be reduced to a minimum.

5. The foregoing description is directed solely towards the construction illustrated, but I desire it to be understood that I reserve the privilege of resorting to all the mechanical changes to which the device is susceptible, the invention being 10 defined and limited only by the terms of the appended claims.

I claim:

1. In a swift, bearing means, arms provided with yarn engaging surfaces spaced about said bearing means as a center, and means for adjustably securing said arms to said bearing means to permit of adjustment to vary the peripheral size of the swift, and yielding means tending to move said arms to expanded position, and adjustable stop means located to be free from interference with a contracting movement of the arms but limiting the expansion of said arms.

2. In a swift, a pair of members arranged in crossing relation and pivoted together at their point of crossing, two pairs of arms, each pair pivoted together at one of their ends with their other ends pivoted one to each of the ends of said members, additional arms each also pivoted to one of the ends of said members, guide means 30 for said additional arms each also pivoted to the ends of said members through which each of said additional arms extend, yarn holders on the outer ends of all of said arms forming a six point bearing for the yarn, said holders being moved 35 toward and from said pivot for the members by a swinging of said members about their pivot whereby the size of said swift is varied.

3. In a swift, a pair of members arranged in crossing relation and pivoted together at their point of crossing, two pairs of arms, each pair pivoted together at one of their ends with their other ends pivoted one to each of the ends of said members, additional arms each also pivoted to one of the ends of said members, guide means 45 for said additional arms each also pivoted to the ends of said members through which each of said additional arms extend, yarn holders on the outer ends of all of said arms forming a six point bearing for the yarn, said holders being moved toward and from said pivot for the members by a swinging of said members about their pivot whereby the size of said swift is varied, resilient means at the pivot for said members tending to relatively move said members to move the yarn holders to expanded position.

4. In a swift, a pair of members arranged in crossing relation and pivoted together at their point of crossing, two pairs of arms, each pair pivoted together at one of their ends with their other ends pivoted each to one of the ends of said members, additional arms each also pivoted to an end of said members, guide means for said additional arms each also pivoted to one of the ends of said members through which each of said additional arms extend, yarn holders on the outer ends of all of said arms forming a six point bearing for the yarn, said holders being moved toward and from said pivot for the members by a swinging of said members about their pivot whereby the size of said swift is varied, resilient means at the pivot for said members tending to relatively move said members to move the yarn holders to expanded position, and adjustable stop means for limiting said expansion to a desired position.

5. In a swift, a pivot pin, a pair of relatively movable hubs rotatably mounted on said pin, a spring contained within said hubs tending to rotate them in one direction, a pair of members pivotally mounted on said pin and crossing each other and extending in different directions, one of said members being secured to one hub and the other member secured to the other hub, arms secured to the ends of said members and yarn holders on the ends of said arms.

6. In a swift, a pivot pin, a pair of relatively movable hubs rotatably mounted on said pin, a spring contained within said hubs tending to rotate them in one direction, a pair of members pivotally mounted on said pin and crossing each other and extending in different directions, one of said members being secured to one hub and the other member secured to the other hub, an arm and a guide secured to the ends of each member, the arm secured to one member extending through the guide at the end of another member, and yarn holders on the ends of said arms.

7. In a swift, a pivot pin, a pair of relatively movable hubs rotatably mounted on said pin, a spring contained within said hubs tending to rotate them in one direction, a pair of members pivotally mounted on said pin and crossing each other and extending in different directions, one of said members being secured to one hub and the other member secured to the other hub, an arm and a guide secured to the end of each member, the arm secured to one member extending through the guide at the end of another member, two pairs of arms each pivoted together with their ends secured to the ends of two of said members, yarn holders at the point of pivoting together, and yarn holders at the end of said arms.

8. In a swift, a pivot pin, a pair of relatively movable hubs rotatably mounted on said pin, a spring contained within said hubs tending to rotate them in one direction, a pair of members pivotally mounted on said pin crossing each other and extending in different directions, one of said members being secured to one hub and the other member secured to the other hub, arms secured to the ends of said members and yarn holders on the ends of said arms, and adjustable stop means for limiting the expansion to a desired position.

9. In a swift, a pivot pin, a pair of relatively movable hubs rotatably mounted on said pin, a spring contained within said hubs tending to rotate them in one direction, a pair of members pivotally mounted on said pin and crossing each other and extending in different directions, one of said members being secured to one hub and the other member secured to the other hub, an arm and a guide secured to the end of each member, the arm secured to one member extending through the guide at the end of another member, yarn holders on the ends of said arms, and adjustable stop means on one of said arms for limiting said expansion to a desired position.

10. In a swift, a pivot pin, a pair of relatively movable hubs rotatably mounted on said pin, a spring contained within said hubs tending to rotate them in one direction, a pair of members pivotally mounted on said pin and crossing each other and extending in different directions, one of said members being secured to one hub and the other member secured to the other hub, an arm and a guide secured to the end of each member, the arm secured to one member extending through the guide at the end of another member.

ber, two pair of arms each pivoted together with their ends secured to the ends of two of said members, yarn holders at the end of said arms, and adjustable stop means on one of said arms 5 for engaging its guide and limiting the expansion to a desired position.

11. In a swift, bearing means, a plurality of members adjustably secured to said bearing means and movable relatively to each other to 10 vary the peripheral size of the swift, arms adjustably secured to said members and provided with yarn-engaging surfaces, and an adjustable stop means secured to one of said arms to act as an abutment to the portion carried by one of 15 said members and prevent said members and arms from moving beyond the desired adjusted position but permitting said members and arms to be moved to reduce the peripheral size of the swift.

12. In a swift, bearing means, a plurality of 20 members adjustably secured to said bearing means, and arms adjustably secured to said members and provided with yarn engaging surfaces, an adjustable stop means secured to one of said arms, and means on one of said members for 25 engaging said stop means to prevent said arms from moving beyond the desired adjusted position in one direction.

13. In a swift, bearing means, members radially directed with reference to said bearing means and 30 movable relatively to each other about said bearing means, and arms secured to said members and provided with yarn-engaging surfaces positioned for supporting yarn in generally circular form about said bearing means as a center, yielding

means for urging said members and arms to expanded position, and adjustable means including a stop on one of said arms for limiting the expansion thereof to a predetermined size.

14. In a swift, a pair of members arranged in crossing relation and pivoted together at their point of crossing, four yarn holders arranged in two pairs, means for connecting said holders to the ends of said members comprising for each holder a pivotal connection to one member and 10 a slideable connection to the other member to cause the holders of each pair, as the arms rotate about their pivot, to approach and recede from each other along straight parallel lines, and whereby one pair of holders approaches and 15 recedes from the other pair along a line at right angles to the motion of a given pair simultaneously with the relative motion of the holders of each pair, a third pair of holders located in a line through the pivot of said members, and 20 means connecting each to a pair of ends of said members so as to approach and recede from the pivot of the members simultaneously with the approaching and receding movements of said first-mentioned pairs with respect to each other. 25

15. In a swift, a pair of pivoted members, and a pair of yarn holders, means connecting said holders to two ends of said members comprising a pair of arms in opposite relation each having pivotal connection to one member and a guide 30 on the other member, whereby said holders approach and recede from each other as said ends recede from and approach each other.

ARVID F. PEARSON.
